UNITED STATES PATENT OFFICE.

WALTER HOHAGEN, OF FALKENSEE, NEAR SPANDAU, GERMANY, ASSIGNOR TO SIEMENS-SCHUCKERTWERKE GESELLSCHAFT MIT BESCHRANKTER HAFTUNG, OF SIEMENSSTADT, NEAR BERLIN, AND ELSEWHERE, GERMANY, A CORPORATION OF GERMANY.

ROTARY PUMP.

Application filed November 13, 1924, Serial No. 749,653, and in Germany November 26, 1923.

My invention relates to improvements in rotary pumps and more particularly in multiple rotary pumps and consists of a sealing device comprising an auxiliary liquid for

5 preventing leakage losses owing to the flow of the supply medium from one pump chamber into another.

It is well known that for delivering gases rotary pumps, impeller pumps, gear pumps, 10 pumps with sliding vanes and the like are employed in which a storage chamber, generally located above the discharge opening of the pump, contains an auxiliary liquid for sealing the pump, such as water, oil or 15 mercury. For some purpose it is advantageous to combine two or more pumps of this kind so that a multiple pump is formed, the individual pumps of which have a common drive but must otherwise be independent 20 of one another.

Owing to the compact combination of the individual pumps particularly difficulties arise in regard to the provision of a satisfactory seal between the individual working 25 chambers. A flow of the medium to be delivered from one pump chamber into the other must be avoided as far as possible by preventing that the auxiliary liquid in one of the sealing chambers of one of the pumps 30 is sucked off by the other pump and thereby a shortage of auxiliary liquid arises in the former. In this manner a satisfactory working of the individual pump in question is rendered impossible. If it is desired to 35 avoid this drawback by improving the seal a complicated and expensive construction is necessary particularly in pumps with great differences in pressure heads. Such sealing devices also cause a considerable 40 consumption of power and never work quite satisfactorily.

The object of my invention is to avoid the mentioned drawback.

My invention consists essentially in putting the storage chambers for the auxiliary or sealing liquid in communication with one another in order to provide a continuous balance of the auxiliary liquid in the various chambers so that a shortage of sealing liquid in any individual chamber cannot occur under any circumstances.

In the drawing affixed to this specifica-

tion and forming part thereof two embodiments of my invention are illustrated by way of example. These drawings represent 55 in:

Fig. 1, a longitudinal section through a duplex pump.

Fig. 2, a transverse section through the 60 same.

Fig. 3, a longitudinal section through a slightly modified construction and

Fig. 4, a transverse section through the same.

Similar parts are indicated by the same 65 numbers of reference throughout all the figures of the drawing.

Referring to Figs. 1 and 2 of the drawings, 11 and 12 are the working spaces of the individual pumps within which rotate 70 the eccentrically disposed piston barrels 13 and 14 upon the common shaft 15. The partition wall between the two working chambers consists, for instances, of the two parts 16 and 17. The intake branches are indicated by the reference characters 18 and 19. Above the piston barrel are disposed the storage chambers 20 and 21 which open into the delivery branches 22 and 23. The two storage chambers 20 and 21 are in communication by the bore 24 so that the auxiliary liquid is free to flow from one to the other in order to balance any shortage. 75

If the improvement is to be applied to rotary pumps with pistons adapted to slide in the piston barrel the piston barrels for the individual pumps may according to my invention in known manner be carried out as single continuous cylindrical roller. In this construction the balancing connection 80 between the storage chambers of the individual pumps is of particular importance because the distance between their working chambers is comparatively very small and a sucking off of the auxiliary liquid from one pump into the other is particularly liable to occur. 85

Such a construction is illustrated in the Figs. 3 and 4. The piston barrels for the individual pumps are here combined into 100 a cylindrical roller 25. The working chambers 11 and 12 are separated one from each other by a partition wall 26. Otherwise the construction and arrangement is the same

as in the Figs. 1 and 2. By providing the bore 24 putting the storage chambers 20 and 21 in communication the sucking off of the auxiliary liquid from one of the sealing chambers is again prevented.

What I claim as my invention is:—

1. A multiple rotary pump having adjacent pump chambers and commonly driven piston rotors disposed thereon, an intake 10 and a discharge port for each chamber and a storage chamber connected to each discharge port and containing sealing liquid, and means for connecting the several storage chambers to equalize the sealing liquid 15 in said storage chambers.
2. A multiple rotary pump having adjacent pump chambers and commonly driven piston rotors disposed thereon, an intake

and a discharge port for each chamber and a storage chamber connected to each discharge port and containing sealing liquid, the several storage chambers being connected by a communicating duct, to equalize the sealing liquid in said storage chambers. 20

3. A multiple rotary pump having adjacent pump chambers and pistons rotors consisting of a rotary cylinder passing thru all pump chambers, an intake and a discharge port for each chamber and a storage chamber connected to each discharge port and containing sealing liquid, said storage chamber being connected by a communicating duct, to equalize the sealing liquid in 25 said storage chambers. 30

In testimony whereof I affix my signature.
WALTER HOHAGEN.
